UNITED STATES PATENT OFFICE.

ABRAHAM PIASER, OF ELMHURST, NEW YORK, ASSIGNOR TO ROSENWASSER BROS., INC., OF ASTORIA, NEW YORK, A CORPORATION OF NEW YORK.

NAIL-EXTRACTING APPARATUS.

Application filed December 18, 1919. Serial No. 345,854.

To all whom it may concern:

Be it known that I, ABRAHAM PIASER, residing at Elmhurst, county of Queens, and State of New York, have invented certain new and useful Improvements in a Nail-Extracting Apparatus, of which the following is a specification.

This invention relates to a new and improved machine adapted for use in the manufacture of boots and shoes, and one of the objects of the invention is to provide a machine which will automatically pull or extract from the last or other parts of the shoe, the nails or brads which are required to be temporarily employed in the production of the shoe, such for instance as the nails or brads as are employed to attach the outer and inner soles to the wooden last about which the shoe is formed.

Hitherto in the manufacture of shoes it has been necessary to employ labor for the purpose of manually extracting the nails or brads used temporarily as above stated in the manufacture of shoe. By the present invention, however, a shoe manufacturer is able to dispense with manual labor in performing this operation, and to substitute the machine of the present invention, thereby effecting a great saving of time and labor in the manufacture of boots and shoes.

Other objects and aims of the invention, more or less specific than those referred to above, will be in part obvious and in part pointed out in the course of the following description of the elements, combinations, arrangements of parts and applications of principles, constituting the invention; and the scope of protection contemplated will be indicated in the appended claims.

In the accompanying drawings, wherein I have illustrated a preferred form of embodiment of my invention:

Figure 1 is a view in elevation, showing my improved machine.

Figure 2 is an end elevation thereof.

Figure 3 is a sectional view taken on the line 3—3 of Figure 2, looking in the direction of the arrows.

Figure 4 is a sectional view taken on the line 4—4 of Figure 1, looking in the direction of the arrows; and

Figure 5 is a sectional view taken on the line 5—5 of Figure 1, looking in the direction of the arrows.

Referring now to the drawings, wherein

similar reference characters refer to similar parts throughout the several views thereof, the reference numeral 1 indicates a portion of the base of the machine, which is adapted to rest upon the floor, said base having a table or platform 2, upon which is erected the standards 3 and 4, the upper ends of which carry a block 5, which form the base of the machine proper, a frame 6 carrying the operative parts thereof. The machine is driven by a constantly driven pulley 7, by means of the belt 8, from a suitable source of power, said pulley 7 being loosely mounted upon a drive shaft 9, with which it is intermittently connected by means which will now be described. The pulley and shaft may be connected and disconnected by means under the control of the operator.

The shaft 9 is provided with an integrally formed collar 10, located adjacent the pulley 7, said collar and the shaft 9 forming a recess 11, in which travels a pin 12, the shank 13 of which is threaded into an aperture provided in the hub of the pulley. The shaft 9 extends through the upper portion 14 of the frame and at its end is provided with an eccentric 15, which works in a plate 16 to reciprocate the plunger block 17, which carries certain of the operative parts of the apparatus.

It will be noted that upon each rotation of the shaft 9 the plunger block 17 will be given a complete reciprocation. Mounted to slide in a groove 18, provided in the shaft 9, is a connecting pin 19 normally urged to outward movement into the recess 11 by means of a plunger pin 20, actuated as by means of a spring 21 said pin and spring being located in a recess which communicates with the groove 20 in which slides a connecting pin 19.

It will be noted that when the pin 19 is permitted to slide outwardly the end thereof will be thrust into the path of the pin 12 carried by the pulley 7, whereby said pulley and shaft 9 will be operatively connected.

Pin 19 is normally held in the retracted position by its engagement with the end of a cam lever 22, pivotally mounted upon a post 23, carried by the frame of the machine, the cam portion 24 thereof engaging with a cam surface 25 formed on the forward face of a lug 26, extending laterally of the pin 19. The lever arm 22 is actuated by a rod 27, guided in a bracket 28, and normally held in

position, as shown, by means of a spring 29, which operates between the bracket 28 and a shoulder 30 formed on said pin, the pin 27 being connected at 31 to the cam lever 22.

5 With the parts in the position shown in Figure 1 of the drawings, it will be noted that the cam portion 24 of the lever 22, engaging the cam surface 25 of the connecting pin 19, holds the latter pin in the position 10 shown in the drawings, against the stress of the plunger spring 21. This permits the pulley 7 to rotate freely without affecting any of the mechanism of the machine.

15 The lower end 32 of the rod 27 is connected at 33 with one end of an operating lever 34, the latter being pivoted as at 35 to the block 5. The opposite end 36 of the lever 34 is provided with a lateral extension 37 so formed as to be engaged with the sole 20 of a shoe.

Clamped as at 38 to a block 39, carried by the plunger block 17, is an arm 40 of a gripper device to which the opposite arm 41 is pivotally attached at 42. The lower ends of 25 the members 40 and 41 are turned inwardly so as to form gripper fingers 42' and 43, which are adapted to engage with the nail or brad to be removed from the sole of the shoe, or other article upon which the machine is adapted to operate.

The reference numeral 44 denotes an outstanding arm secured to the frame of the machine, as at 45, the end of which carries a roller 46 adapted to co-operate with a cam 35 portion 47 of the arm 41 of the gripper device, so that when the plunger block 17 is lifted by the eccentric 15, the roller 46 remaining stationary, will cause the arms 40 and 41 of the gripper device to separate, 40 forcing the gripper members 42' and 43 into engagement with the nail or brad which is to be extracted from the sole of the shoe, or other article. The roller 46 rides upon a plane surface 48 of the arm of the gripper 45 device during this operation. Fastened to the frame of the machine, at 49, and extending forwardly therefrom, is a stop arm 50, the function of which is to limit the upward movement of the sole or heel of a boot or shoe when the brads or nails thereof are engaged by the gripping device during the 50 operation of extracting them.

The reference numeral 51 denotes the sole 55 of a shoe containing the nails or brads which are to be extracted therefrom, held by the hand of the operator, indicated at 52, in a position to be operated upon, and the reference numeral 53 denotes a receptacle into which the nails or brads are discharged 60 when they have been extracted from the sole or heel of a boot or shoe. A retractile spring 54 operates to pull the ends of the arms 40 and 41 toward each other so as normally to separate the gripping fingers 42' and 43.

65 Having thus described the construction of

this embodiment of my invention, the operation thereof, which should be largely understood, is as follows:—

Assuming the parts to be in the position shown in Figure 1, the operator engages the sole of the boot or shoe with the end 37 of the lever arm 36 with the nail or brad to be drawn located directly beneath the gripper arm 42' and 43. The shoe is then moved upwardly pushing the lever arm 36 in a corresponding direction which compels a downward movement of the arm 27 and a swinging movement of the cam 22, whereby the cam surface 24 thereof is disengaged from the opposing cam surfaces 25 of the locking pin 19. These parts being disengaged, the spring 21 acting through the plunger pin 20, forces the pin 19 forward into the path of the pin 12 carried by the pulley so that the latter will engage the connecting pin 19 and 75 compel a rotated movement of the shaft. The upward movement of the shoe has carried the nail or brad to be drawn, between the gripper members 42' and 43, and the shaft 9 being now connected with its driving mechanism, the eccentric 15 will be rotated to cause an upward movement of the plunger block 17, thereby bodily moving the gripping device comprised by the arms 40 and 41 upwardly, the roller 46 riding on the 80 cam surface 47 of the arm 41, causing the gripping members 42' and 43 to grip the nail or brad and extract the same from the shoe or heel of the boot or shoe, inasmuch as the upward movement of the latter will be 85 limited by its engagement with the arm 50.

When the parts are allowed to resume their normal positions, the lever arm 36 being forced downwardly by the spring 29 engaging with the shoulder 30 of the rod 27, the end of the cam 24 will be again thrown in the path of the cam 25, thereby retracting the connecting pin 19 from its position in engagement with the pin 12 of the pulley 7, 90 thus automatically disconnecting the operative parts of the mechanism.

It will therefore be seen that I have provided a device well adapted to attain, among others, all the ends and objects pointed out in an exceedingly simple and efficient manner, by means of which the manual labor hitherto necessary in the operation of the manufacture of shoes is entirely eliminated, my improved machine working substantially 100 automatically and taking the place of several manual laborers, performing the work in an expeditious manner, and effecting a saving of the brads, which drop into the receptacle 53, and which can be again utilized 105 to perform a similar function.

As many changes could be made in this construction without departing from the scope of the following claims, it is intended that all matter contained in the above description or shown in the accompanying 110

drawing shall be interpreted as illustrative only and not in a limiting sense.

Having thus described my invention what I claim as new and desire to secure by Letters Patent is:

1. In a machine of the class described, the combination with gripping means, of means for operating said gripping means including a shaft, driving means normally disconnected from said last mentioned means on said shaft to establish an operative connection between said shaft and said driving means, and means adapted to be engaged and raised upwardly by the work to actuate said connecting means whereby said gripping operating means will be driven by said driving means. 70
2. In a machine of the class described, the combination with a plunger, of a pair of opposed gripping members carried thereby, a shaft for operating said plunger, driving means mounted upon said shaft and normally disconnected therefrom, means carried by said shaft and adapted to establish an operative connection between said shaft and said driving means, and means adapted to be engaged and raised upwardly by the work to actuate said connecting means to operate said plunger to bodily move said gripping members, and means for causing a relative movement of said gripping members to close the latter. 75
3. In a machine of the class described, the combination with a plunger, of a pair of opposed nail gripping members carried by said plunger, a shaft adapted to operate said plunger, a pulley mounted upon said shaft, said shaft and pulley being normally disconnected, means carried by said shaft adapted to be moved into position to connect the latter with said pulley, means normally holding said last named means out of engagement with said pulley, and means adapted to be engaged by the work for moving said last named means to such position that the means upon the shaft will be engaged by the pulley, whereby movement of the shaft will effect an operation of said plunger, and thereby of said gripping members, and means for causing an independent relative movement of said gripping members when the same are moved bodily by said plunger. 80
4. In a machine of the class described, the combination with a plunger, of a pair of nail gripping members carried thereby, a shaft for operating said plunger, a pulley loosely mounted upon said shaft, said shaft and pulley being provided with a pair of opposed parts adapted when engaged to effect an operative connection between said shaft and pulley, means for moving the part carried by said shaft into the path of the part carried by said pulley, means for normally holding the part carried by the shaft out of engagement with the part carried by the pulley, and means adapted to be engaged by the work for moving the part carried by the shaft, into engagement with the part carried by the pulley, said shaft when operatively connected with said pulley being adapted to operate said plunger, to move said nail gripping means bodily from the work, and means for causing a relative movement of said gripping means to cause the latter to grip and extract a nail carried by the work. 85
5. In a machine of the class described, the combination with a pair of gripping members, said gripping members being bodily movable and also relatively movable, of a movable support for said gripping members, means for moving said support, and means adapted to be engaged by the work for effecting an operation of said last mentioned means, the construction and arrangement being such that said gripping members will be moved to and from the work, and means for moving said gripping members toward each other during their bodily movement in one direction. 90
6. In a machine of the class described, the combination with a movable support, of a pair of nail gripping members carried thereby, means for driving said support to effect a bodily movement of said gripping means to and from the work, means for moving said gripping members toward each other during the movement of said support in one direction, and from each other during a movement of said support in the opposite direction, and means projecting below said nail-gripping members and having a portion arranged to engage the work and to be moved upwardly by the work thereby actuating the said support-driving means. 95
7. In a machine of the class described, the combination with a movable support, of a gripping device carried thereby, said gripping device comprising a pair of opposed pivotally mounted arms, the lower ends of which are provided with gripping fingers, said support being adapted when operated to move said gripping members toward and from the work, means for moving said gripping members toward and from each other during their movement toward and from the work, and means adapted to be engaged by the work for effecting a reciprocatory movement of said support. 100
8. In a machine of the class described, the combination of a reciprocating member, of driving mechanism for reciprocating the said member, a loose power-operated pulley, means engaging the work below the said gripping device whereby an upward movement of the work against the said engaging means connects the said pulley and the said driving mechanism, a gripping device carried by said member comprising a pair of 105
- 110
- 115
- 120
- 125
- 130

- opposed arms, pivoted together intermediate their ends and having depending gripping fingers adapted to be engaged with a nail carried by the work, means for causing said support to move said gripping device to and from the work, and means for causing a relative movement of said arms during their bodily movement, to cause their gripping fingers to engage with a nail carried by the work and caused to extract the same therefrom.

9. In a machine of the class described, the combination with a nail gripping device, comprising a pair of lever arms pivoted intermediate their ends and having depending gripping fingers located in position to engage a nail carried by the work, of means for effecting a bodily movement of said gripping device toward and from the work and for effecting a relative movement of said members, to cause said gripping members to engage a nail and extract it from the work, a driven shaft, means on said shaft to connect said shaft operatively with said first named means, and means extending below the gripping device and constructed to engage and to be moved upwardly by the work to actuate said connecting means.

10. In a machine of the class described, the combination of a movable carrier, a gripping device supported thereon, said

gripping device comprising a pair of lever arms pivoted intermediate their ends and having depending gripping fingers, driving means for reciprocating said movable carrier, a loose power-driven pulley, means constructed to engage the work and to be moved upwardly by the work for effecting the connection of the pulley and said driving means, and means for effecting a gripping action between said gripping fingers during the movement of said carrier.

11. In a machine of the class described, the combination of a movable carrier, a gripping device supported thereon, said gripping device comprising a pair of lever arms pivoted intermediate their ends and having depending gripping fingers, driving means for reciprocating said movable carrier, means for effecting a gripping action between said gripping fingers during the movement of said carrier, a shaft adapted to reciprocate said carrier, constantly driven means mounted upon said shaft and normally disconnected therefrom, and means adapted to be engaged by the work for effecting a driving engagement between said constantly driven means and said shaft.

In testimony whereof I affix my signature.

A. PIASER.

Witness:

EMMA WEINBERG.
